UNITED STATES PATENT OFFICE.

PHILIPPE WENTZEL AND HENRY BLETZER, OF BOSTON, MASSACHUSETTS.

CAR-FENDER.

SPECIFICATION forming part of Letters Patent No. 487,547, dated December 6, 1892.

Application filed September 12, 1892. Serial No. 445,605. (No model.)

To all whom it may concern:

Be it known that we, PHILIPPE WENTZEL and HENRY BLETZER, both citizens of the United States, and residents of Boston, in the 5 county of Suffolk and State of Massachusetts, have jointly invented new and useful Improvements in Car-Fenders, of which the following, taken in connection with the accompanying drawings, is a specification.

This invention relates to life-saving car-fenders for cable, electric, or other motor-propelled street-cars, and has for its object the prevention of serious injury to persons or animals that may be struck by the car; and it 10 is carried out as follows, reference being had to the accompanying drawings, wherein—

Figure 1 represents a perspective view of a street-car, showing the improved car-fender held in its normal position thereon; and Fig. 20 2 represents a similar view showing the cradle or catcher released and swung upward for receiving a body or object after being struck by the fender.

Similar letters refer to similar parts wherever they occur on the different parts of the drawings.

A represents a motor-propelled car of any suitable construction, and B represents the front end or cross-beam of the platform, as 30 usual. To the end of the car or its platform or cross-beam are secured or pivoted a pair of forwardly-projecting, preferably curved, brackets C C, which are connected together, preferably, by means of lateral stays or braces C' C', 35 as shown in the drawings. To the upper ends of the brackets C C is pivoted the curved cradle or catcher D, having, preferably, attached to its upper end a lateral brace or shaft d, the ends of which are journaled in bearings in the brackets C C, as shown. The said curved cradle may be made of sheet metal in whole or part, or covered with wire-netting or other suitable material, or padded, if so desired, without departing from the essence of 45 our invention.

D' is a lateral brace or cross bar secured to the lower forward end of the cradle or catcher D, which is normally locked in the position shown in Fig. 1 by means of a transverse 50 rocker-bar E, pivoted to the lower front ends of the brackets C C and having one or more lips e e, projecting over the brace D', as shown in Fig. 1.

F F are springs which serve to instantly swing the cradle or catcher D upward as soon as its lower end is released from the rocker-bar E and its locking lips or projections. In the drawings we have shown such springs as coiled ones located on the shaft or brace d and pressing against the front end of the car; 60 but this is not essential, as other forms of springs may be used, if so desired.

The front end of the car above the fender may be cushioned or padded to more effectively prevent injury to persons or bodies 65 struck by the moving car.

The operation is as follows: Supposing that the spring-pressed cradle or catcher D is swung downward and locked in position by means of the rocker-bar E and its lips or projections, as shown in Fig. 1, if, as the car moves forward, an object or person is struck by the rocker-bar E, it will cause the latter to turn forward, thus releasing the cradle or catcher D, which receives the person or object and swings upward by the influence of its springs to the position shown in Fig. 2, 70 thus holding the person on the cradle and preventing him or her from dropping off, and allows such person to rest securely on said 75 cradle until the car can be stopped. After a person or object has been removed the cradle or catcher D is swung downward, as shown in Fig. 1, and locked in position by means of the rocker-bar E, as hereinbefore mentioned. 80 85

Having thus fully described the nature, construction, and operation of our invention, we wish to secure by Letters Patent and claim—

In combination with the brackets C C, the spring-actuated cradle or catcher D, pivoted 90 at its upper end, and a locking-bar pivoted to the lower end of said brackets and adapted to normally hold said cradle or catcher in position, substantially as and for the purpose set forth. 95

In testimony whereof we have signed our names to this specification, in the presence of two subscribing witnesses, on this 9th day of September, A. D. 1892.

PHILIPPE WENTZEL.
HENRY BLETZER.
